RAILWAY MAIL DELIVERY DEVICE

Paul Bernstein, Roanoke, Va.

Application October 5, 1943, Serial No. 505,071

4 Claims. (Cl. 258—15)

My invention relates to the delivery of railway mail, and particularly to the delivery and reception of mail by a train in motion, at one and the same time.

Devices have been made heretofore for the delivery and for the reception of mail; but most of these have not been found to be entirely satisfactory, either practically or economically. The operation of discharging and receiving mail bags is not without risks to life and limb, and to loss of equipment. A loaded mail bag may weigh from 25 pounds to as much as 70 pounds; and the impact of such a bag, hurled even at the moderate speed of 50 miles per hour, is considerable. This impact has been partly taken up by compression buffers of steel or of rubber or both. Spring buffers are more enduring than are those of rubber; but the recoil from them is almost as severe as is the impact of the load.

On single track roads, and on roads where there is no means for turning a car, the mail car and its mail receiving and discharging equipment will not be positioned to receive and to discharge when moving in both directions. To meet this condition duplicate sets of receiving and discharging apparatus have in the past been provided, which has added to the cost and weight of the apparatus and to the difficulty of operation. In many cases bags have been discharged by simply throwing them out of the door; a dangerous and an expensive custom.

Objects of my improved device for discharging and for receiving railway mail are: to provide a reversible device for the discharging and receiving which may be used when the train or mail car is traveling in either direction; to provide a device having similar and interchangeable parts to reduce the cost of equipment and of upkeep; to provide a device which shall be inexpensive to make, and to maintain; and in which heavy impacts and stresses shall be countered.

In the drawings:

Figure I shows my device arranged on the side of a mail car and when not extended for use.

Figure II is a vertical section on line *a—b* in Figure I.

Figure III is a view similar to Figure II, but with the device extended for use in discharging and receiving mail bags.

Figure IV is a front elevation of my device for discharging and receiving mail bags arranged on a standard beside a railroad track, but not extended for use.

Figure V is a side view of the device shown in

Figure IV; but with parts extended for discharging and receiving mail bags.

Figure VI is a detail, to a larger scale, showing in front elevation, and part section, the discharging and receiving head.

Figure VII is the same detail as in Figure VI, but in plan, and part section.

Figure VIII is the same detail as in Figure VI; but is side elevation and part section.

In Figures I, II and III the numeral 2 indicates the open door of a mail car. A heavy rotatable bar 4 is supported in bearings 6, which bearings are adjustable as to their height upon the brackets 8. Upon the bar 4 is fixed the head 10, which head has a lower part 12, shown in Figure VI as fitted to it by dowel pins, or which may be fitted to head 10 by other means as described later.

Attached to the lower part 12 of the head 10 is the receiving hook-arm 20, which comprises the hook-head 16, the hook-bight 14, and the hook-plate 18. Upon the hook-plate 18 is pivoted at 22 the delivering arm 24. A spring 26 is arranged to hold the arm 24 in a normally horizontal position, as shown in the drawings, while allowing movement on the pivot 22, to be explained later herein. The hook-arm 20 extends a distance sufficient to catch a mail bag hanging on the station standard when the hook-arm is thrown into the position shown in Figure III.

On the back of the head 10 is fixed a handle or lever 28. When the operator pulls this handle down he swings the head 10 with its parts from the position shown in Figures I and II to that shown in Figure III.

Pivoted at 9 in the recess 11 in the lower part 12 of the head 10 is a latch 30, designed to allow the bag to pass into the bight 14, and to prevent it bounding out of the said bight. On being struck by a bag, coming in from the right as one views the drawings in Figures I and VI, the latch is thrown to the left. The bag having passed the latch 30 into the bight 14, the latch 30 will resume its outwardly extending position, to close the bight 14; and it will be restrained from further movement, to the right, by the latch heel 13 coming against the squared surface 15.

Rubber or spring buffers 5 on the bar 4 take up some of the force of the impact.

Below the apparatus described above is a second heavy rotatable bar 40, carried in bearings 42 which are adjustable on brackets 44, bolted to the door framework of the mail car; as shown in Figures I, II, and III.

On the bar 40 is fixed the arm 46; at the farther end of which is pivoted at 48 the arm 50.

The arm 50 may be thrown over to one side or to the other side of the arm 46, coming to rest on the bracket 52. The arm 50 is of substantially the same length as the arm 24. Upon these two arms, when extended as in Figure III, the mail bag is hung for delivery from the mail car. A tension spring 54 is arranged on arms 46 and 50 to hold the arm 50 against the bracket 52. When bar 40, in Figure II, is rotated clockwise, the arms 46 and 50 are thrown from position shown in Figures I and II to that shown in Figure III. There is a reason for the use of the spring 26 (Figs. I and VI) and of the spring 54 shown in Figure I. When the two arms 24 and 50 are extended, as in Figure III, it is more than likely that the bag shown (Fig. III) will not be moving directly towards the receiving arm 92 mounted on the track standard and directly towards the receiving arm 92 mounted on that standard (Fig. IV). When that is the case the receiving arm 92 will give the bag a violent pull or jerk towards itself. When that happens, the spring-controlled arms 24 and 50 "give" towards the receiving arm 92, and no damage is done to the bag or to its supporting arms. Any tendency of the bag to double on itself is taken up by the swinging balance of the heads on bearings 6 and of the bar 46 on bearings 42.

A link 60 is carried by arm 62, secured to bar 4, and by arm 64 secured to the bar 40. When the operator pulls down on the lever 28, the bar 4 is rotated anti-clockwise, and arm 62 is thrown upwards. The link 60 then pulls up the arm 64, which then rotates bar 40 clockwise, and throws the arm 46 to the position shown in Figure III. That is to say: by pulling the lever 28 down, the head 10 with its parts are thrown into position to receive a bag, and arms 24 and 50 are in position to hold a bag for delivery. The bag is shown in dotted lines in Figures III and V. This link motion is so proportioned that the lower head and arm when swung outwardly as in Figure III will slightly overbalance the weight of the upper head and arm together with the weight of the bag supported on arms 24 and 50. This makes a floating balance between arms 24 and 50; and this balance, with the spring controlled "give" or arms 24 and 50 form a universal resilient support for the mail bag, which will give to any horizontal force exerted against the bag.

Figures IV and V show an arrangement of parts like those shown in Figure I; except for the relative positions of the delivering and the receiving parts, which are now reversed as to their positions one above the other.

In Figure IV the upper bar 70 is carried in bearings 72, and to it is fixed the arm 74, to the end of which is pivoted at 75 the arm 76. From this arm 76 is to be hung the bag of mail to be caught up by the apparatus on the mail car.

A lower bar 78 is carried in bearings 80; and on this bar is fixed the head 82, similar to head 10, and having a lower part 84 similar to part 12 on head 10. Receiving-bight 86 is similar to bight 14; head 88 is similar to head 16; hook-plate 90 to hook-plate 18; and hook-arm 92 to hook-arm 20. Also note the pivoted arm 94 similar to pivoted arm 24.

The parts so far noted in Figures I and IV are 70 interchangeable; for instance, lower head 12 with its parts 14, 16, 18, 20, 24, for lower head 84 with its parts 86, 88, 90, 92, 94. Also the arms 46 and 50 are interchangeable with arms 74 and 76.

An exception is in the upper head 10 and the 75

upper head 82, which differ in shape somewhat, the latter being the narrower for economy of space; and in that to its upper end is fixed, or is made a part, the arm 83, which takes the place of crank 62 in Figure II.

To the bar 70 is fixed a crank 100, being an extension of the arm 74; and to the head 82 is fixed the crank 83, which is fixed on the bar 78. To bar 78 is also fixed a lever 96, by pulling down on which the head 82 is thrown into its horizontal and operating position, shown in Figure V.

A cross-link 102 connects crank 100 to crank 83 at pivots 85 and 87 in the manner shown in Figure V; so that when, by pulling down on lever 96, the head 82 is thrown upward into a horizontal position, the crank 100 and arm 74 will be thrown downward to a horizontal position. Stop plates 101 and 103 limit the swing of the cranks 100 and 83.

The cross-link 102 is made elastic in its length, to compensate for changes in the distance between pivots 85 and 87 when throwing the apparatus into operating position, by means of the compression spring 104 within tubular case 106 and so arranged under head 108 of link-member 110 that when the link is thrown from non-operating to operating position the change in length will be compensated by increased compression of the spring.

The operation is simple: a mail-bag to be delivered from car to station is hung on extended arms 24 and 50, while the mail-bag to be delivered from station to car is hung on arms 76 and 94. The hook-arms 20 and 92 are in the extended position. As the train passes the station, the hook-arm 20 (attached to the mail car) seizes the bag hanging on arms 76 and 94, while the hook-arm 92 (attached to the station standard) seizes the bag hanging on arms 24 and 50. Turning now to Figures VI to VIII, inclusive, of the drawings: here is shown in larger detail the parts of the head 10, and of the head 82; and particularly those features which enable me to reverse the heads so that they shall function when the mail car is traveling up or down the line.

I have already described the reversing of the bag-holding arms 50 and 76; but it is also necessary to reverse the positions of arms 24 and 94, as well as the positions of hook-arms 20 and 92. This I do by reversing the lower heads 12 and 84 on their respective upper heads 10 and 82. What has been said of the reversing of head 12 on head 10 applies also to the reversing of head 84 on head 82.

Receiving hook-head 16 has secured in it two rods 17 and 19, which fit and slide in bores 21 and 23 in lower head 12. Rod 19 does not necessarily pass through lower head 12, but only forms a guide, to prevent head 16 turning on rod 17. Rod 17 does pass through head 12; and a sufficient distance through head 12 to support a compression spring 25, held in place by the head 27; of which head more in detail later. A bag having been caught by hook-arm 20, it is caught in the bight 14; and the impact between bag and head 16 is taken up in part by the compression spring 25. Rod 19 may if desired be extended through head 12 to support a second compression spring. The recoil of the head 16 due to the spring 25 is severe. This I counteract by treating the head 27 as a piston, causing it to slide with a neat fit into an air cylinder 29. At a point intermediate the ends of the cylinder 29 is a small aperture 31 which allows compressed air to escape from the cylinder until the said

aperture is covered or passed by the piston 27. The remaining air in the cylinder is then still more compressed by the head 27, and acts as an air-cushion to counteract the force of the recoil.

It will also be noted that, by a judicious placing of one or more apertures 31 in the cylinder 29, the impact of the bag and the recoil can both be cushioned.

The upper head 10 and the lower head 12 part on the line 33. A heavy pin 35 is seated rotatably in the bore 37 in lower head 12. An annular groove 39 cut in pin 35 is engaged by pin 41 which passes through head 12, and which holds pin 35 in bore 37 while allowing the head 12 to swivel on the pin 35.

The pin 35 also extends into the bore 43 in the upper head 10; in which bore it is slideable but not rotatable. It is held from turning in head 10 by cutting away its metal on one side, as at 45; so that pin 41, passing through head 10, shall prevent its turning, while allowing it to slide within the bore 43.

When the heads 10 and 12 are together at the line 33 the upper end of pin 35 extends into the upper end of the bore 43 in head 10. A locking-pin 49 passes through head 10 and also through the end of pin 35. The lower head 12 is thus held in contact with upper head 10.

To prevent the turning of lower head 12 on upper head 10 when they are together, as in Figures I and IV, I can use a rabbet-joint, or tongue-and-groove, or the dowel pins shown in the drawings. These dowel pins, 51 and 53, can be seated in either head 10 or 12 and enter holes 55 and 57 in the other.

Upon the arrival of the mail car at one end of the trip, it is only necessary to remove locking-pin 49, pull down lower head 12 until stopped by shoulder 59 of pin 35 engaging pin 41, swing head 12 on pin 35 until its direction is reversed. Then push head 12 again up against upper head 10, the dowel pins entering their seats; and reinstate the locking-pin 49. This locking-pin can be secured in any simple manner. I have shown a pivoted lug 61, as a means for preventing accidental removal of the locking-pin 49.

To lessen the cost of manufacture, when using die-castings instead of using the dowel pins 51 and 53 to make the connection between the head 10 and the lower head 12, I form a rabbet or tongue-and-grooved joint between the contacting surfaces of the two heads. This is a simple and a strong means for connecting the heads which can be made by die-castings without any further machine work.

It is usual to fit spring-keepers to arms such as 24, 50, 76 and 94 for the purpose of holding the bags in place, lest they be blown off the arm by a strong wind. These keepers are not shown in Figure I, II, III, IV, V, and VIII, as the scale is too small; but in Figures VI and VII they are shown on the arm 24 and are indicated by the numeral 7.

The herein described device for the receiving and the delivering of railway mail by trains in motion is automatic; it can be operated in any kind of weather. The operator does not have to "aim" it; when set it will operate without further manipulation. On the train or on the ground any inexperienced hand can set it. There is a

large clearance between the device and the locomotive cab window, a want of which has in past times led to serious accidents. The cost of the parts is small; and because of the interchangeability of parts the storage of few extra parts is necessary and changes are quickly made. The mail clerk is in no danger; and his work is expedited.

I claim:

1. In a device for receiving and for discharging railway mail bags: the combination of a main head attached to the mail car; a second head swiveled on the main head; a receiving arm adapted to catch a mail bag, and having an extension adapted to slide in the second head and projecting beyond the second head; spring means on the said extension adapted to absorb impact from the catching of the mail bag; cylinder and piston means for absorbing the recoil of the impact absorbing means; and means for locking the swiveled head on the main head.

2. The combination of a main head attached to the mail car; a second head swiveled to the main head; a receiving arm adapted to catch a mail bag, and having an extension adapted to slide in the second head and projecting beyond the second head; compression spring means on the said extension adapted to absorb impact due to the catching of a mail bag; cylinder and piston means for absorbing the recoil of the impact absorbing means; a supporting arm pivoted to the receiving arm and adapted to support a bag to be delivered; spring means to hold the supporting arm in position to deliver a bag; and means for locking the swiveled head to the main head.

3. In combination: a main head; a second head swiveled to the main head; means for locking and unlocking the swivel joint between the second head and the main head; a receiving arm slidably attached to the second head and extending beyond the second head; means associated with the receiving arm extension for absorbing impact from the catching of a bag; cylinder and piston means for absorbing recoil of the impact absorbing means; latch means pivoted in the second head and cooperating with the second head and the receiving arm to retain the caught bag.

4. In a railway mail delivery device: the combination of a head mounted on a support and adapted to swing outwardly therefrom; a mail bag receiving arm slidably mounted on the head and having an extension beyond the head; means on the extension for absorbing impact of a bag on the arm; means on the extension for absorbing recoil of the impact absorbing means; a bag holding arm pivoted on the receiving arm; spring means to control the position of the bag holding arm; a second head mounted on a support below the first head and adapted to swing outwardly from its support; a second bag holding arm pivoted on the outer end of the second head; spring means for controlling the position of the said second bag holding arm: the positions of the first and second bag holding arms being such that the pivoted arms afford a resilient support for the bag to be delivered.
